EXPANDING CLAMP FOR A TUBE BENDING MACHINE

Ernest F. Mellinger, San Diego, Calif., assignor to The Ryan Aeronautical Co., San Diego, Calif., a corporation of California

Application February 1, 1954, Serial No. 407,350

6 Claims. (Cl. 153—80)

The present invention relates generally to metal working equipment and more particularly to an expanding clamp for a tube bending machine.

In present types of tube bending machines one end of the tube being bent is clamped between jaws while the tube is formed around a grooved block. A considerable straight length of the tube must be held in the jaws to ensure a firm grip during the bending operation, and the tube must be held by considerable pressure. The straight portion of the tube held between the jaws is often cut off and discarded after the bending operation, a process which is wasteful and costly. Moreover, this portion of the tube is often damaged by the clamping pressure of the jaws, this being particularly true when bending light gauge tubing. The present invention enables a tube to be held firmly at the end with a minimum of waste material and also prevents damage to the tube by crushing in the jaws of the machine.

The primary object of this invention is to provide an expanding clamp which positively secures the end of a tube being bent by locally expanding and clamping the tube between interfitting beaded and grooved elements in the bending machine.

Another object of this invention is to provide an expanding clamp which is adjustable so that the straight portion of tube clamped in the machine may be varied to any required length.

Another object of this invention is to provide an expanding clamp which may be fitted to many existing types of tube bending machines and which may be constructed in any required size to accommodate standard tube sizes.

Finally, it is an object to provide an expanding clamp of the aforementioned character which is simple, safe and convenient for workmen to operate, and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawings which form a material part of this disclosure and wherein similar characters of reference indicate similar or identical elements and portions throughout the specification and throughout the views of the drawings and in which:

Fig. 1 is a perspective view of the expanding clamp assembly attached to a tube bending machine.

Fig. 2 is an end elevation view of the device.

Fig. 3 is a top plan view.

Fig. 4 is an enlarged sectional view taken on the line 4—4 of Fig. 2.

Fig. 5 is an enlarged fragmentary view of a portion of Fig. 4, showing more clearly the expanding mandrel clamping the end of a tube.

Fig. 6 is a fragmentary sectional view taken on the line 6—6 of Fig. 5.

2

Referring now to the drawings, the structure of the device includes a clamp jaw 10 and a forming jaw 12, which are secured to the frame 14 of a conventional tube bending machine, shown fragmentarily in Figs. 2 and 3 for reference purposes. The clamp jaw 10 has a semi-circular groove 16 and the forming jaw 12 has a corresponding semi-circular groove 18, so that when the jaws are clamped together the grooves form a cylindrical bore 20 in which the tube to be bent is inserted. 5 The forming jaw 12 has an arcuate end 22 with a forming groove 24 incorporated therein and comprising an extension of the groove 18.

The expanding clamp comprises a fluid pressure actuating cylinder 26 of conventional design, having an extending piston rod 28. Secured in the end of the piston rod 28 is an expander pin 30 which passes through an expanding mandrel 32. The mandrel 32 rests on a support tube 34 having an integral base plate 36, which is secured against the end of the actuating cylinder 26. 15 Secured to the actuating cylinder 26 is a bracket 38 carrying a roller guide 40, which is slideable on a guide rail 42 mounted on one side of the forming jaw 12. This guide rail 42 assists in aligning the mandrel 32 for axial adjustment in the bore 20.

20 The bracket 38 has a substantially L-shaped portion 44 having at the ends thereof lugs 46 and 48. The upper lug 46 is secured to the base plate 36 while the lower lug 48 is secured to an attachment plate 50 on the lower end of the actuating cylinder 26, suitable screws 30 51 and 52 being used for the attachment. The upper portion of the bracket 38 is extended outwardly to provide a face plate 54. The roller guide 40 comprises a generally U-shaped channel 56, one side of which is extended to constitute a clamp plate 58 having a pair of parallel slots 60 therein. The roller guide 40 is secured to the bracket 38 by bolts 62 and nuts 64, the slots 60 permitting radial adjustment of the roller guide relative to the actuating cylinder 26. Within the channel 56 are rollers 66 rotatably mounted on pins 68 to provide a friction free contact against the guide rail 42.

25 The guide rail 42 is secured to a pair of spaced support bars 70 extending outwardly from a mounting plate 72 secured to the side of the forming jaw 12 by means of screws 74. At the lower end of the guide rail 42 is 30 a stop pin 76 to limit the downward movement of the actuating cylinder and expanding mandrel assembly.

The mandrel 32, shown best in Figs. 5 and 6, comprises four segments 78 of a cylinder having a tapered central bore 80. The segments 78 collectively have 35 an outwardly projecting annular bead 82 adjacent the upper end thereof and an inwardly disposed annular groove 84 spaced below said bead. The segments are biased inwardly by a spring 86 fitted in the groove 84.

The expander pin 30 comprises a tapered head 88 40 shaped to fit the bore 80 of the mandrel 32. Extending downwardly from the head 88 is a shank 90 having a screw threaded end 92 which is screwed into the end of the piston rod 28.

The support tube 34 is fitted with a pair of inwardly 45 projecting retaining screws 94 adjacent the upper end to prevent inadvertent removal from the expander pin 30.

The inside of the bore 20 has a plurality of spaced ring grooves 96 shaped similarly to the contour of the bead 82. These ring grooves 96 are located so that the 50 upper groove is aligned with the bead 82 when the base plate 36 is flush against the lower surface of the forming jaw 12 and clamp jaw 10. In order to utilize the remaining ring grooves 96, spacing washers 98 are fitted over the support tube 34 between the base plate 36 55 and the jaws 10 and 12, said spacing washers being equal in thickness to the distance between the individual ring grooves.

The device is, of course, suitable for bending a particular size of tubing, the bore 20 being a close fit for the tubing. Present types of bending machines utilize interchangeable jaws to fit the various standard sizes of tubing, and it should be understood that the expanding mandrel assembly may also be constructed in different sizes.

As illustrated in the drawings, a tube 100 is inserted into the bore 20 until the end of the tube extends slightly below the bead 82, the expanding mandrel assembly being inserted from below and held against the lower surface of the jaws 10 and 12. Pressure is then applied to the actuating cylinder 26 to retract the piston rod 28, so pulling the tapered head 88 downwardly through the mandrel 32 and forcing the segments 78 outwardly so that the bead 82 forces the tube 100 into the ring groove 96, as shown in Figs. 4 and 5.

When interconnecting lengths of tubing which have been bent, a certain length of straight tubing is necessary at each end to facilitate attachment of the couplings or the like. The straight length may be varied in the present device by adding or removing spacing washers 98 to control the depth to which the mandrel assembly is inserted in the bore 20. In the drawings, two of these spacing washers 98 are shown as an example, the bead 82 being aligned with the second ring groove 96 below the uppermost ring groove. When no spacing washers 98 are used, the bead 82 is, of course, aligned with the uppermost ring groove 96.

With the end of the tube 100 clamped tightly by the mandrel 32, the tube is bent around the forming groove 24 as shown in dotted line in Fig. 4. The tube is bent with the aid of a conventional forming mouse or the like, the construction and use of which are fully understood by those skilled in the art. When the tube is bent to the required position, the pressure in the actuating cylinder 26 is released or reversed causing the piston rod 28 to extend. The segments 78 are pulled inwardly by the spring 86, so releasing the bead 82 from the tubing compressed into the ring groove 96. The jaws 10 and 12 are then opened to facilitate removal of the tube 100. The only waste portion of the tube 100 is the fractional end portion containing the formed bead, which may be removed in a suitable manner to leave the required length of tube.

The roller guide 40 and guide rail 42 assist the alignment of the mandrel 32 when the assembly is inserted in the bore 20, and also stabilize the actuating cylinder 26 throughout the complete range of adjustment. The slots 60 permit considerable radial adjustment of the roller guide 40 so that a single actuating cylinder 26 may be used with several sets of jaws and mandrels.

It will be evident that the present device may be installed on many types of conventional tube bending machines or incorporated therein by machining the necessary ring grooves 96 in the existing jaws 10 and 12 and adding the guide rail 42 and its supporting structure to each forming jaw 12.

The operation of this invention will be clearly comprehended from a consideration of the foregoing description of the mechanical details thereof, taken in connection with the drawing and the above recited objects. It will be obvious that all said objects are amply achieved by this invention.

Further description would appear to be unnecessary.

It is understood that minor variations from the form of the invention disclosed herein may be made without departure from the spirit and scope of the invention, and that the specification and drawing are to be considered as merely illustrative rather than limiting.

I claim:

1. In a tube bending machine, separable jaws having confronting faces defining a substantially cylindrical bore therebetween, said faces having grooves therein, said grooves being spaced apart a uniform distance axially

of said bore, a segmented mandrel slidable in said bore, an outwardly extending bead on said mandrel, said grooves being shaped and positioned to receive said bead, a tapered expander pin longitudinally slidable in said mandrel, traction means operatively connected to said expander pin for longitudinal movement thereof, a bracket fixed to said traction means, a guide rail mounted on one of said jaws, said bracket being slidable on said guide rail longitudinally relative to said bore, spacers between said traction means and said jaws to adjust the longitudinal position of said mandrel in said bore, said spacers having a thickness dimensionally equal to the distance between said grooves, whereby said mandrel may be held with said bead selectively aligned with said grooves.

2. In a tube bending machine, separable jaws having confronting faces defining a substantially cylindrical bore therebetween, said faces having grooves therein, said grooves being spaced apart a uniform distance axially of said bore, a segmented mandrel slidable in said bore, an outwardly extending bead on said mandrel, said grooves being shaped and positioned to receive said bead, a tapered expander pin longitudinally slidable in said mandrel, a fluid actuated cylinder having an extended piston rod, said expander pin being attached to said piston rod, a rigid support tube between said cylinder and said mandrel, and spacers between said cylinder and said jaws to adjust the longitudinal position of said mandrel in said bore, said spacers having a thickness dimensionally equal to the distance between said grooves, whereby said mandrel may be held with said bead aligned with individual grooves.

3. In a tube bending machine, separable jaws having confronting faces defining a substantially cylindrical bore therebetween, said faces having grooves therein, said grooves being spaced apart a uniform distance axially of said bore, a segmented mandrel slidable in said bore, an outwardly extending bead on said mandrel, said grooves being shaped and positioned to receive said bead, a tapered expander pin longitudinally slidable in said mandrel, a fluid actuated cylinder having an extended piston rod, said expander pin being attached to said piston rod, a rigid support tube between said cylinder and said mandrel, a bracket fixed on said cylinder, a guide rail mounted on one of said jaws, said bracket being slidable on said guide rail longitudinally relative to said bore, and spacers between said cylinder and said jaws to adjust the longitudinal position of said mandrel in said bore, said spacers having a thickness dimensionally equal to the distance between said grooves, whereby said mandrel may be held with said bead aligned with individual grooves.

4. In a tube bending machine, separable jaws having confronting faces defining a substantially cylindrical bore therebetween, said faces having grooves therein, said grooves being spaced apart a uniform distance axially of said bore, a segmented mandrel slidable in said bore, an outwardly extending bead on said mandrel, said grooves being shaped and positioned to receive said bead, a tapered expander pin longitudinally slidable in said mandrel, a fluid actuated cylinder having an extended piston rod, said expander pin being attached to said piston rod, a rigid support tube between said cylinder and said mandrel, a bracket fixed on said cylinder, a radially adjustable roller guide on said bracket, a guide rail mounted on one of said jaws, said roller guide being slidable on said guide rail longitudinally relative to said bore, and spacers between said cylinder and said jaws to adjust the longitudinal position of said mandrel in said bore, said spacers having a thickness dimensionally equal to the distance between said grooves, whereby said mandrel may be held with said bead aligned with individual grooves.

5. In a tube bending machine, separable jaws having confronting faces defining a substantially cylindrical bore

therebetween, said faces having grooves therein, said grooves being spaced apart a uniform distance axially of said bore, a segmented mandrel slidable in said bore, an outwardly extending bead on said mandrel, said grooves being shaped and positioned to receive said bead, a tapered expander pin longitudinally slidable in said mandrel, a fluid actuated cylinder having an extended piston rod, said expander pin being attached to said piston rod, a rigid support tube between said cylinder and said mandrel, a bracket fixed on said cylinder, a radially adjustable roller guide on said bracket, a guide rail mounted on one of said jaws, said roller guide being slidable on said guide rail longitudinally relative to said bore, a stop pin in said guide rail to limit the travel of said roller guide, and spacers between said cylinder and said jaws to adjust the longitudinal position of said mandrel in said bore, said spacers having a thickness dimensionally equal to the distance between said grooves, whereby said mandrel may be held with said bead aligned with individual grooves.

6. In a tube bending machine, separable jaws having confronting faces defining a substantially cylindrical bore therebetween, said faces having grooves therein, said grooves being spaced apart a uniform distance axially of said bore, a segmented mandrel slidable in said bore,

15

20 25

an outwardly extending bead on said mandrel, said grooves being shaped and positioned to receive said bead, a tapered expander pin longitudinally slidable in said mandrel, a fluid actuated cylinder having an extended piston rod, said expander pin being attached to said piston rod, a rigid support tube between said cylinder and said mandrel, inwardly projecting screws in said support tube to retain the same on said expander pin, and spacers between said cylinder and said jaws to adjust the longitudinal position of said mandrel in said bore, said spacers having a thickness dimensionally equal to the distance between said grooves, whereby said mandrel may be held with said bead aligned with individual grooves.
